UNITED STATES PATENT OFFICE.

CHARLES F. STODDARD, OF NEW YORK, N. Y., ASSIGNOR TO AMERICAN PIANO COMPANY, OF NEW YORK, N. Y., A CORPORATION OF NEW JERSEY.

DUST-COLLECTING VALVE MECHANISM FOR PLAYER PIANOS.

Application filed June 1, 1923. Serial No. 642,747.

This invention relates to automatic musical instruments, and pertains more particularly to an improved pneumatic construction for valve mechanisms.

It has been found, in the operation of automatic instruments of the pneumatic type, that the action of valve mechanisms for controlling actuating pneumatics is often seriously impaired by the admission of dust particles thereto which clog various passages and openings and thus reduce their effective size. Difficulty is experienced particularly in this respect in the bleed openings, which because of their restricted size are particularly susceptible to this trouble.

One of the objects of this invention is to provide a device which will serve to separate dust particles drawn into the valve mechanism from the air admitted and collect them in order to prevent clogging of bleed openings and other parts of the mechanism.

The accompanying drawings show a valve structure constituting a preferred embodiment of the invention selected for purposes of illustration, in which, Figure 1 is a sectional view of the valve mechanism showing diagrammatically an actuating pneumatic connected thereto; and

Figure 2 is a sectional view on the line 2—2 of Figure 1.

Referring to the drawings, the block 1 is provided with an exhaust chamber 2 which may be connected to suitable source of exhaust in the usual manner not here described. Above the block 1 is block 3 which is provided with a valve chamber 4 which is normally connected to atmosphere through the port 5. This chamber may, however, be connected to the exhaust chamber 2 through the port 6. Communication between the valve chamber 4 and either atmosphere or exhaust is controlled by the valve 7 operatively connected with the stem 8. Leading from the valve chamber 4 is the passage 15 to which may be connected any suitable pneumatic means which it is desired to operate as, for instance, the pneumatic 14, to which may be connected a striker mechanism or an expression valve mechanism.

Beneath the block 1 is a third block 9 which is provided with a diaphragm chamber 10, one side of which is closed by the diaphragm 11. The other side of the valve 55 chamber may be closed by the plate 12 which may be fastened to the block 9 by any suitable means such as the screws 13, for instance.

An inlet opening 16 is provided to the diaphragm chamber 10 and is arranged tangentially thereto, as shown. This opening is connected with a tracker bar 17 in the usual manner by the tube 17. The diaphragm chamber 10 is also provided with 60 an opening 18 connected with the passage 19 and which is connected with the exhaust chamber 2 by a suitable bleed opening 20. The opening 18 is arranged approximately 65 in the center of the diaphragm chamber 10. 70 In the lower part of the diaphragm chamber 10 and arranged below the openings 16 and 18 are the crossed baffle plates 21, the number of which may vary, two being shown here as a convenient number. 75

The operation of the valve mechanism is similar to other old and common mechanisms. When the exhaust chamber 2 is subjected to exhaust, the chamber 10 will also be subjected to exhaust through the bleed 80 opening 20. The valve 7 therefore will remain seated over port 6 due to its own weight, since the pressures on opposite sides of the diaphragm are equalized through the bleed 20. When, however, atmospheric air 85 is admitted to the diaphragm chamber 10 through the tracker tube 17 this balance is destroyed because atmospheric air is admitted faster than it can be withdrawn through the bleed opening. Valve 7 will be raised, 90 therefore, cutting off communication between valve chamber 4 and atmosphere, and opening communication to the exhaust chamber 2. Pneumatic 14 or other suitable pneumatic means will therefore be collapsed 95 in the usual manner.

In the present device, however, the tangential position of the opening 16 with respect to the chamber 10 will impart a rotary motion to the air admitted from the tracker 100 tube 17 causing a swirling action thereof within the upper part of the chamber. The air in the

lower part of the chamber, however, will be kept substantially quiet by the baffle plates 21. As particles of dust or other foreign matter are drawn into the chamber 10 through the opening 16, this rotary or swirling motion of the air will cause it to pass over some distance before it is withdrawn through the opening 18. Particles of dust, therefore, will drop from the swirling air into the comparatively still air between the baffle plates 21 and will be retained there. It will also be noted that the rotary motion of the air will impart a centrifugal force on the dust particles tending 15 to throw them toward the outside periphery of the diaphragm chamber, thus serving an additional separating function, since air is withdrawn from approximately the center of the chamber in which there would be a 20 minimum of dust. The dust collected in this manner may be easily removed at suitable intervals by removal of the plate 12.

It is to be understood that the invention is not limited to the precise embodiment 25 herein shown and described, as for instance, the valve mechanism may form a unitary structure as shown, or it may form simply a single mechanism of a bank of valve mechanisms as is common in the art. On 30 the contrary, the invention is capable of various modifications within the scope of the subjoined claims.

I claim as my invention:

1. In a player piano, the combination with 35 a tracker bar, tracker duct, and valve operated thereby, of a chamber interposed between said tracker bar and valve; means for admitting air thereto and imparting to the air thus admitted a circuitous motion in part of said chamber only.

2. In a player piano, the combination with 45 a tracker bar, tracker duct, and valve operated thereby, of a chamber interposed between said tracker bar and valve; an opening for admitting air thereto arranged at one side of the chamber to impart to the air thus admitted a circuitous motion; and means in said chamber for opposing said twisting motion in part of said chamber.

3. In a player piano, the combination with 50 a tracker bar, tracker duct, and valve operated thereby, of a chamber interposed between said tracker bar and valve; an opening for admitting air thereto and imparting to the air thus admitted a circuitous motion; and an outlet opening through which air may be withdrawn from said chamber, said outlet opening being located near the center of said chamber.

4. A pneumatic construction for player 60 pianos, comprising, in combination, a substantially cylindrical diaphragm chamber; an inlet passage thereto arranged substantially tangentially to said chamber; an outlet opening therefrom substantially in the

center of said chamber; and baffle plate means in said chamber for opposing motion of the air in a portion of said chamber.

5. In a player piano, the combination with a tracker bar, tracker duct, and valve 70 operated thereby, of a chamber interposed between said tracker bar and valve; an inlet opening through which air is admitted to said chamber; an outlet opening through which air is exhausted from said chamber; and means in said chamber for opposing motion of the air in a portion of said chamber.

6. In a player piano, the combination with a tracker bar, tracker duct and valve operated thereby, of a chamber interposed between said tracker bar and valve and having inlet and outlet ports constructed and arranged at one side and substantially at the center of the chamber respectively to cause 80 the air to travel an extended path within said chamber, whereby dust particles or other foreign matter may be collected in said chamber.

7. A pneumatic construction for player 90 pianos, comprising, in combination, a substantially cylindrical diaphragm chamber, an inlet passage thereto substantially tangential to the periphery of said chamber, and an outlet opening therefrom substantially in the center of said chamber.

8. In a player piano, the combination with a tracker bar, tracker duct and valve operated thereby, of a chamber interposed between said tracker bar and valve; means for admitting air to said chamber arranged to impart a centrifugal force to particles of foreign matter suspended therein tending to throw them to the outside of said chamber, and means for withdrawing air from the 105 center of said chamber.

9. In a pneumatic valve mechanism, a diaphragm chamber, means for admitting air to the upper part thereof, restricted means for withdrawing air from the upper 110 part thereof, and means in the lower part of said chamber for maintaining the air in substantially quiet condition.

10. In a player piano, the combination with a tracker bar, tracker duct, and valve operated thereby, of a chamber interposed between said tracker bar and valve; an outlet port from said chamber; and means for admitting air to said chamber and causing it to travel an extended path to said outlet port.

11. A pneumatic construction for player 120 pianos having a tracker bar, tracker duct and valve operated thereby, comprising, in combination, a substantially cylindrical chamber interposed between said tracker bar and valve; an inlet passage thereto; an outlet opening therefrom; said inlet passage being arranged substantially tangentially to said chamber whereby air admitted is caused to travel a circuitous path.

12. In a player piano, the combination with a tracker bar, tracker duct, and valve operated thereby, of a chamber interposed between said tracker bar and valve; inlet and outlet passages in the upper part of said chamber; said inlet passage being connected to the tracker bar; and means in the

lower part of said chamber for opposing motion of the air therein.

In testimony whereof, I have signed my ¹⁰ name to this specification this 24th day of May, 1923.

CHARLES F. STODDARD.
